ATTORNEYS

UNITED STATES PATENT OFFICE.

JOSEPH B. GOERLING, OF WAUSAU, WISCONSIN.

PENCIL ATTACHMENT.

Application filed April 30, 1923. Serial No. 635,694.

To all whom it may concern:

Be it known that I, JOSEPH B. GOERLING, a citizen of the United States, and a resident of Wausau, in the county of Marathon and State of Wisconsin, have invented a new and Improved Pencil Attachment, of which the following is a full, clear, and exact description.

This invention has relation to an attachment for writing instruments and relates more particularly to a pencil attachment which will serve in a number of various capacities when associated with or applied to a pencil.

The principal object of the present invention is to provide an attachment of the character described, which when associated with the pencil will greatly facilitate the work of a clerk in pencil checking and paging a ledger, saving of time for erasures and which will further function to provide a positive grip in writing, in addition to acting as a clip for retaining the pencil in a pocket.

As a further object the invention aims to provide an attachment of the character described which is extremely simple in its construction, inexpensive to manufacture, and which is highly efficient in its purpose.

With the above recited and other objects in view, the invention resides in the novel construction set forth in the following specification, particularly pointed out in the appended claim and illustrated in the accompanying drawing, it being understood that the right is reserved to embodiments other than those actually illustrated herein to the full extent indicated by the general meaning of the terms in which the claim is expressed.

In the drawing—

Figure 1 is a perspective view of the attachment alone.

Fig. 2 is a rear view of the same.

Fig. 3 is a view illustrating the attachment associated with a pencil and employed in the capacity of a clip.

Fig. 4 is a view of the same when used for making an erasure.

Fig. 5 is a perspective view illustrating

the same used as a means for facilitating 50 the paging of a ledger.

Referring to the drawing by characters of reference the attachment comprises a tubular split member 10 which is formed at one end with a laterally offset arm 11, the free extremity of which is provided with right angularly bent parallel side wings 12 having ears or lugs 13 bent inwardly toward each other to associate therewith an eraser 14. The device is preferably stamped from a single sheet of resilient material whereby the arm 11 is yieldable with respect to the member 10 and the member 10 is of sufficient resiliency to frictionally embrace a pencil to which it is applied by engagement thereover. A portion of the outer face of the member 10 is roughened or serrated as at 15 to provide, when applied to the pencil, a non-slip surface with which the index finger is engaged while writing or checking. 70 When the attachment is associated with the pencil A adjacent the upper end or remote from the point B the spring arm 11 serves in the capacity of a clip for clamping engagement with a pocket C as illustrated in 75 Fig. 3. When using the pencil for writing, checking or the like, the attachment is moved toward the pointed end B as illustrated in Figs. 4 and 5, thus disposing the body member 10 with the roughened or serrated portion 15 in a position to act as a non-slip rest for the index finger. The extremity of the arm 11 which carries the eraser 14 will then dispose said eraser in a convenient position to rapidly perform its function. At 85 the same time the eraser will be disposed in a convenient position to be used for turning the pages of the ledger as illustrated in Fig. 5.

From the foregoing it will thus be seen 90 that the attachment facilitates the operations of checking, writing, paging or erasing, by slightly changing the relative position of the attachment upon the pencil, thereby effecting real economy in the time and 95 labor of a clerk.

I claim:

An attachment for writing instruments,

comprising an instrument-embracing member mounted for longitudinal movement on the instrument and having an offset resilient arm extending beyond one end thereof, 5 and a rubber carried by the free end of said arm, constituting, respectively, an eraser and a pager disposed in spaced relation to the writing end of the instrument when the

arm is projected beyond said end, whereby the writing, erasing or paging may be accomplished without adjustment of the attachment, the said rubber also constituting a non-slip means for engaging the pocket when the free end of the arm is disposed alongside the writing implement.

JOSEPH B. GOERLING.
